UNITED STATES PATENT OFFICE.

ROSE MARKS, OF NEW YORK, N. Y.

COMBINED ABDOMINAL BANDAGE AND CORSET.

No. 906,249.

Specification of Letters Patent.

Patented Dec. 8, 1908.

Application filed September 17, 1907. Serial No. 393,413.

To all whom it may concern:

Be it known that I, ROSE MARKS, a citizen of the United States, residing in the city, county, and State of New York, have invented a certain new and useful Improvement in a Combined Abdominal Bandage and Corset, of which the following is a specification.

This invention has especial relation to a form of corset to be used by persons requiring abdominal support whether by reason of obesity or on account of pathological conditions.

The principal object of the invention is the provision of efficient means whereby a corset can be adapted to perfect support of the parts named without undue discomfort to the wearer and whereby all the necessary adjustments can be easily and quickly performed by the wearer herself.

In the accompanying drawing, Figure 1 shows the corset spread out as viewed from the interior, showing the bandage in place, and Fig. 2 is a partial view of the exterior, showing the preferred arrangement of fastening ribbon.

In carrying out my said invention I am able to adapt any form of corset to the improvement and for this purpose I employ a bandage or supporter suited as to size, shape and texture (whether elastic or not) to the particular wearer to be fitted, and I secure the two extreme edges or ends of this bandage within the corset on the two sides at such a height as suits the prospective wearer.

At 1 and 2 are shown the two halves of a corset, laced together as usual, as at 3. The bandage of flexible textile material is shown at 4.

I prefer to secure the lateral ends of the bandage as follows. Eyelet holes duly reinforced, as by strips 5 are provided at the side of the corset and preferably toward the front of the wearer. On one side of the bandage a reinforcing strip 6 is fastened directly to the bandage, while on the other side two strips 6 and 8, united by the flexible textile sheet 7 are adapted to be united to the bandage by hooks and eyes 9. The strips 6 are secured to the perforated reinforcing strips 5 by lacings 10 and 11, the ends of which are carried outside of the corset and tied as shown in Fig. 2 or otherwise.

The lower edge of the bandage is held down so as to come under the parts to be supported by means of bands 12, 13, extend-

ing from this lower edge of the bandage to the upper edge of the wearer's stockings, being preferably provided with eyes 14 lapped over buttons 15 on the bandage at the upper ends 60 and carried around and behind the legs of the wearer.

It will be seen that my improvement supplies an elastic bandage for support of the abdomen which can be drawn down by the straps 13 to stretch it under the projecting abdominal parts; also that my bandage can be raised or lowered to fit the wearer by appropriate use of the side lacings. These side lacings are furthermore easily handled from outside, without removing the corset, so as to loosen or tighten the whole bandage or one portion more than another, at will. At the same time, in undressing, the bandage can be quickly opened along the hooks and 75 eyes 9, without taking the trouble to unlace the same.

What I claim is:

1. An abdominal belt comprising a corset portion, an elastic belt secured to said corset portion at two vertical edges and adapted to be inclosed by said corset, and means for detachably securing said belt directly to the inner face of said corset, whereby when said belt is detached, all objectionable attaching 85 portions are avoided.

2. An abdominal belt, comprising in combination with a corset, an elastic belt portion adapted to be inclosed in the front portion of said corset, adjustable lacing means securing 90 said belt to said corset, means for fastening or unfastening said belt independently of said lacing means, and straps depending from said belt for attachment to the wearer's stockings, whereby said belt may be held in proper position at its lower portion.

3. An abdominal belt, comprising in combination with a corset, an elastic belt portion adapted to be wholly inclosed by said corset and comprising two sections of unequal 100 width, adjustable lacing means securing said belt to said corset, means for fastening or unfastening said belt independently of said lacing means, and means for holding the lower portion of said belt in position, said 105 independent belt fastening means comprising hooks and eyes on the corresponding vertical edges of said belt sections.

ROSE MARKS.
